UNITED STATES PATENT OFFICE

141,269

DESIGN FOR A SPLASH GUARD

Mattie L. Strong, Chicago, Ill.

Application February 5, 1945, Serial No. 117,766

Term of patent 14 years

(Cl. D7—7)

To all whom it may concern:

Be it known that I, Mattie L. Strong, a citizen of the United States of America, residing at 155 North Clark Street, Chicago, Illinois, have invented a new, original, and ornamental Design for a Splash Guard, of which the following is a specification, reference being had to the accompanying drawing, forming a part thereof.

Referring to the drawing,

Figs. 1 and 2 are side views of opposite sides of a splash guard embodying my new design; Fig.

3 is a front view and Fig. 4 is a rear view of the same.

My splash guard is characterized by its height and protects the stockings of the wearer, and its curved rear to protect the back of the wearer's shoes.

I claim:

The ornamental design for a splash guard, substantially as shown and described.

MATTIE L. STRONG.
